GOLF PUTTER HEAD

James Karban, Jr., 1645 Grove Ave., Berwyn, Ill. 60402

Filed Oct. 6, 1967, Ser. No. 8,883

Term of patent 3½ years

(Cl. D34—5)

FIG. 1 is a perspective view of a golf putter head showing my new design with the broken line showing of a shaft portion being for illustrative purposes only;

FIG. 2 is a top plan view thereof;

FIG. 3 is a front elevational view thereof;

FIG. 4 is a bottom plan view thereof;

FIG. 5 is a rear elevational view thereof;

FIG. 6 is a side elevational view thereof;

FIG. 7 is a top plan view of a modification of the unit of FIGS. 1-6 wherein a recess extends downwards on the back surface of the unit; and

FIG. 8 is a rear elevational view of the modification indicated in FIG. 7.

I claim:

The ornamental design for golf putter head, as shown and described.
